FUEL OIL TANK INTAKE BOX

Armand G. Caruolo, Providence, R. I.

Application March 13, 1948, Serial No. 14,741

4 Claims. (Cl. 220—86)

1

The present invention relates to fuel oil tank installations, and has particular reference to an intake arrangement mounted in the wall of a building.

The principal object of the invention is to provide an oil intake box which may be initially installed during construction, or which may be easily installed in a completed building, and to which the supply pipe to an oil tank and the air vent pipe may be readily attached.

Another object of the invention is to provide a compact oil intake box which is mounted flush with the building wall, and which has no pipes outwardly connected thereto.

With the above and other objects and advantageous features in view, the invention consists of a novel arrangement of parts more fully disclosed in the detailed description following, in conjunction with the accompanying drawings, and more specifically defined in the claims appended thereto.

In the drawings:

Fig. 1 is a front elevation of the novel intake box, as it appears installed in a brick foundation wall;

Fig. 2 is a vertical section through the intake box; and

Fig. 3 is a rear view thereof.

It has been found desirable to provide a compact fuel oil intake box which is mounted in a wall of a building, and which receives the fuel oil nozzle when filling the oil tank, the oil supply line and the vent pipe being secured to the back of the intake box to eliminate unsightly pipe connections outside the building. I have found it feasible to arrange a down flow conduit for the oil and a down flow passageway for the vented air, so that the intake box is of small size and is unobtrusive when installed.

Referring to the drawings, the intake box 10 includes a casing 11 which has generally rectangular walls and may be made of any suitable metal, preferably cast-iron. The face plate 12 of the intake box is preferably rectangular and has a threaded inflow opening 13 in the upper portion thereof which is normally closed by a threaded lock nut 14, the opening 13 communicating with an angularly positioned down flow conduit 15 which leads to a threaded outflow opening 16 in the rear wall 17, the opening 16 having a threaded boss 18 associated therewith to which the supply pipe 19 leading to the oil tank is threaded.

The interior of the box is hollow and constitutes an air vent chamber 20, the upper portion

2

of the chamber having a threaded air inflow opening 21 in the rear wall 17 and an associated threaded boss 22 to which the air vent pipe 23 is threaded, the air passing outwardly from the chamber 20 through air vent slots 24 positioned in the lower portion of the face plate. The lower wall 25 of the chamber 20 preferably slants downwardly towards the face plate and the slots 24 to permit free outward flow of rain or the like which may enter through the slots 24.

The face plate 12 is preferably provided with an edge flange 26 to present an attractive appearance when mounted in the building wall, and the compact design permits dimensioning the box so that it is the height of two standard building bricks, whereby it is readily inset in new constructions and is easily installed in old constructions.

The above described construction thus includes a downwardly extending oil inflow passageway including the inflow opening in the upper portion of the face plate, the angularly disposed conduit, and the outflow opening in the lower portion of the rear plate, and a downwardly extending air vent passageway which includes the air vent opening in the upper portion of the back plate, the interior hollow chamber of the casing, and the slotted openings in the lower portion of the face plate.

Although I have described a specific constructional embodiment of the invention, it is obvious that changes in the size, shape and arrangement of the parts may be made to provide different intake box designs, without departing from the spirit and the scope of the invention as defined in the appended claims.

I claim:

1. An intake box for fuel oil installations comprising a casing of hollow formation having a front plate and a back plate, an oil inflow passageway including an opening in the upper portion of the front plate, an opening in the lower portion of the back plate, and a conduit between said openings, and an air vent passageway including the interior of the casing, an opening in the upper portion of the back plate, and an opening in the lower portion of the front plate.

2. An intake box for fuel oil installations comprising a casing of hollow formation having a front plate and a back plate, an oil inflow passageway including an opening in the upper portion of the front plate, an opening in the lower portion of the back plate, and a conduit between said openings, and an air vent passageway including the interior of the casing, an opening in

the upper portion of the back plate, and a slot in the lower portion of the front plate.

3. An intake box for fuel oil installations comprising a casing of hollow formation having a front plate, said front plate having an inflow opening in the upper portion thereof, a down flow conduit communicating at its upper end with the inflow opening, and a threaded opening in the rear wall of the casing communicating with the lower end of the down flow conduit, the casing having a threaded air vent opening in the rear wall thereof, said front plate having an air vent slot in the lower portion thereof.

4. An intake box for fuel oil installations comprising a casing of hollow formation having a front plate, said front plate having an inflow opening in the upper portion thereof, a down flow conduit communicating at its upper end

5 with the inflow opening, and a threaded opening in the rear wall of the casing communicating with the lower end of the down flow conduit, the casing having a threaded air vent opening in the rear wall thereof, said front plate having an air vent slot in the lower portion thereof and an edge flange.

ARMAND G. CARUOLO.
